UNITED STATES PATENT OFFICE

RICHARD HOWLAND RANGER, OF NEWARK, NEW JERSEY, ASSIGNOR TO RADIO CORPORATION OF AMERICA, A CORPORATION OF DELAWARE

CROSS SCREEN PICTURE RECEIVING SYSTEM

Application filed January 9, 1928. Serial No. 245,350.

The present invention relates to an improvement over the previously known types of picture receiving machines adapted for either wire or radio reception of transmitted pictures, facsimiles, manuscripts, newspaper articles, finger prints, checks, advertising matter, and, in fact, all matter capable of reproduction. In the machines for reproducing these various subject matters of which I will 5 hereinafter use the term "picture" to include all, it has been customary to record by the use of heated jets of air, heated recording points, sparks, marking pens, electrochemical action, and the like in paths which have a 10 parallel relationship one with the other. By this I mean that the reproduced picture was built up by tracing marking pulses either on lines extending parallel to each other in one direction across a recording surface or by lines 15 which were traced on a recording surface as spiral lines by rotating the recording surface and advancing the recording surface at the same time with respect to the recording instrumentality. By my copending application, 20 Serial No. 128,720, filed August 12, 1926, I have illustrated one form of the above described types of recording machines.

In the above described types of recording machines the resulting pictures, while in 25 many ways resembling half-tones, were not close enough to an exact half-tone picture to make themselves readily recognized as such. Also, in machines where there is a reciprocating or spiral motion of the recording instrument with respect to the recording surface 30 there are many difficulties relating to the problem of synchronization between the transmitter and the receiver to be overcome.

It is, therefore, an object of the present invention to produce a picture recording device, capable of receiving pictures and the like over radio or wire, in which the reproduced picture more closely approximates the highly desirable half-tone print.

45 At the same time it is an object of my invention to provide a picture recording device in which the "streaked" effect so prominent in pictures made with the type of receivers above described will be overcome.

50 Still another object of my invention is to

provide a picture receiving device in which it is possible to guide the picture receiving surface into the machine as a continuous strip and thus avoid the time delays which are occasioned by changing from one recording 55 strip to another.

It is also an object of my invention to provide a picture receiving device in which the recording instrumentality assumes both a rotary and a reciprocating motion with respect to the recording surface, and thus traces a path across the recording surface which bears a predetermined angular relationship with respect to the direction of advance of the recording surface. 60

Still a further object of my invention is to provide a recording device for radio or wire transmitted pictures in which the recording device traces a path of marking pulses upon the recording surface at a predetermined angle 65 with respect to the line of advance of the recording strip and in tracing the path of marking pulses first traces a path at the predetermined angle across the recording surface from right to left and then at a later period of time 70 traces a path at the same predetermined angle across the recording surface from left to right. Preferably, the angle should be in the proximity of 45° to the direction of advance of the recording surface, but any other 75 angle is equally suitable, and I believe my invention in its broad terms is capable of being interpreted to cover recording at all angles with respect to either the horizontal 80 or vertical. 85

Still a further object of my invention is to produce a picture receiving device which, especially in the case of radio received pictures, there is increased accuracy of reproduction, due, in part, to the fact that the 90 recording device is made to approach each portion of the recording surface twice for the purpose of marking the intensity of light and shade, or pigmentation, in the originally transmitted picture. This double reproduction of each point in the picture readily adapts the device to increased accuracy of reproduction, since the impulses when received are often distorted, due to the static conditions of the atmosphere, or totally blotted out 95 100

due to fading conditions affecting the signal, and with the double reproduction system these conditions are not likely to be encountered at the two separated time intervals 5 of marking or recording such as are provided by the two angular directions of reproduction.

Still another object of my invention is to arrange a picture receiving and recording device in which the reproduced picture will 10 correspond, in a measure, to the bias line work in photo engraving, as well as a picture which bears the appearance of a composite photograph having the separate lines of reproduction woven in and out at an angle to each 15 other, and at the same time providing an arrangement in which the woven lines of reproduction consist of a series of parallel lines at an angle to another set of parallel lines.

20 Still another object of my invention is to provide a picture receiving apparatus which may be easily and readily changed into a transmitter by merely substituting light sources for the recording means and arranging a lens system within the rotary and reciprocating recording system, so that light may be directed to a light sensitive medium and influence a transmitter system for transmitting intensity variations in light and shade 25 in a picture. In this case the arrangement would be of the character which I have disclosed in my copending application, Serial No. 235,431, filed November 25, 1927, of which this application represents a preferred form 30 of receiving apparatus for coordination therewith.

A further object of my invention is to provide a picture receiving and reproducing apparatus in which the difficulties of excess 40 heat for a heated recording instrumentality are avoided by the provision of a heat radiating surface associated with the heating element.

Still a further object of my invention is to 45 provide a double system of recording jets in which one jet is used for recording in one direction and the other jet is used for recording in the opposite direction.

Still another object of my invention is to 50 provide a system in which there is a single control means for both recording systems.

Still another object of my invention is to provide a picture receiving system in which there are no reversals in mechanical motions 55 necessary for reversing the direction of travel of the recording surface.

Other objects of my invention are to provide in the manner hereinafter set forth a picture transmitting system which is simple in 60 its construction and arrangement of parts, one which is highly durable, compact, efficient in its use, conveniently operated, readily set up, substantially fool proof, inexpensive to install, as well as a system which is readily 65 adapted to increased speed of reproduction

of pictures, and at the same time a system in which the accuracy of reproduction is increased to a high degree.

The novel features which I believe to be characteristic of my invention are set forth in the appended claims. The invention itself, however, both as to its organization and method of operation, together with further objects and advantages thereof, will best be understood by making reference to the following description when read in connection with the accompanying drawings, wherein:

Fig. 1 is a perspective view showing a portion of the front and top of a preferred embodiment of my receiving machine;

Fig. 2 is a view, partly in section, showing the arrangement of the air heating and directing means, and is a view taken through a part of the machine shown in Fig. 1, although Fig. 2 is largely a conventional showing thereof for the purpose of illustrating the principle of operation;

Fig. 3 is a showing of a longitudinal section through the signal actuated recording means;

Fig. 4 is a conventional showing of the arrangement of the recording instrumentalities, showing the signal actuated and the non-signal actuated recording devices; and,

Fig. 5 is a diagrammatic showing of the two sets of recording action upon the continuously advanced recording surface and illustrates, in a conventional manner, the method of building up the recorded picture.

To now make reference to the accompanying drawings, the invention consists essentially in a rotary recording means revolving beneath and advancing transversely with respect to a fixed semicircular plate provided with two slots each making an angle of approximately 45° with respect to the horizontal or to the line of advance of a recording strip which is carried by the fixed semicircular plate for recording picture impulses. Appropriate means for advancing the recording surface with respect to the semicircular slotted plate and the recording apparatus is provided and this may, if desired, be of the nature of that set forth in my copending application, Serial No. 235,431, filed November 25, 1927, although any other preferred form of embodiment may be substituted, such for example as is disclosed by my copending application Serial No. 128,720, filed August 12, 1926.

To now make direct reference to Fig. 1 of the drawings, which I wish to be understood is merely illustrated for the purpose of giving a concrete illustration of an application of the invention although the invention is capable of various modifications and changes such as fairly fall within its scope and disclosure, the arrangement shown has closely followed that disclosed in my copending case,

Serial No. 235,431, above referred to, and is a typical form of receiving device for working with the transmitting device of the cross screen character. A motor and appropriate type of gear reduction mechanism (not shown) is preferably used for driving the shaft 1, provided with the endless spiral slot 2, as well as for rotating the cylinder 3 through the means of worm and gear connections (not shown, since it is not of the essence of the invention and is disclosed by copending application Serial No. 235,431).

Extending longitudinally of the cylinder 3 and substantially the entire length thereof on diametrically opposite sides of the cylinder is a slotted portion 4. A rotary recording head generally designated 5 is carried on and about the rotary cylinder 3 and it is this rotary recording head that carries the signal actuated instrumentalities for producing the picture which corresponds to that picture which is transmitted to the receiver by wire, wired radio, or radio, or any other means of communication from a near or remote point.

The semicircular shaped plate member 7 is curved about the cylinder 3 and the rotary recording head 5 and is arranged so as to carry a continuously advancing recording surface probably of the general character disclosed by my copending application which was filed jointly with R. S. Bicknell as Serial No. 303,108 on August 30, 1928. The semicircular shaped plate member 7 is provided with two slots 8 and 9, each arranged at an angle of approximately 45° to the line of advance of the paper recording strip or at 45° to the axis of the rotary cylinder 3 for a purpose to be hereinafter set forth. The slots 8 and 9 cross at about their mid-point and at the end of each slot there is preferably arranged a sort of reversing curved portion which will also be later described. While I have above set forth that the slots are preferably at an angle of 45° with respect to the vertical and horizontal, this is merely stated for the purpose of illustrating a concrete example of one embodiment of my invention and it is to be understood that any other suitable angle may be substituted for my 45° arrangement and still fall within the scope and objects of the invention.

An arrangement for advancing a recording strip of the character above disclosed over the back surface of the semicircular shaped slotted plate member 7 has been disclosed by my copending application, Serial No. 235,431, filed November 26, 1927, and has not been herein reproduced, but to explain the same briefly it may consist of a series of belts driven at a reduced speed from that of the cam shaft 1 so as to continuously advance, by means of the friction drive, a recording surface, as the cam shaft is rotating. If desired, appropriate means of interrupting the drive and regulating tension of the belts may be

provided as was disclosed by the above named copending application.

As has been above described, the rotary cylinder 3 carries a rotary recording head 5 which is guided with respect to the cylinder 3 in its longitudinal movement by means of rollers which are guided in the longitudinal slot 4. This provides that the rotary recording head 5 must turn at the same rate of speed as the cylinder 3. Also, it is necessary that the rotary recording head 5 be advanced longitudinally of the cylinder 3 for the purpose of producing a recording action back and forth across the surface of the recording medium. I have provided a suitable arrangement for this purpose by means of the guide sleeve 10 which rides upon the cam shaft 1 and has an inwardly extending pin (not shown) resting in the cam slot 2 which is of an endless spiral character so that as the cam shaft is turning the guide sleeve 10 is advanced longitudinally of the cam shaft. By means of the pins 11 extending downwardly from the guide sleeve 10 and resting on either side of a spindle 12, the guide sleeve is unable to assume any rotary motion and all motion derived from the turning of the cam shaft must be that of moving the guide sleeve back and forth longitudinally of the cam shaft. On the rotary recording head 5 and at one end thereof is a slotted or grooved portion 13 in which a pin 14 mounted upon an overhanging bracket 15 carried by the guide sleeve 10 is arranged to slide. It is this pin 14 sliding in the groove or guide slot 13 that carries the rotary recording head 5 back and forth longitudinally of the rotary cylinder 3.

Due to the turning of the cylinder 3, at all times at a slower rate than that of the cam shaft, the rotary recording head 5 is continuously assuming a rotary motion due to the cylinder 3 and a longitudinal motion in direction from left to right and right to left on the cylinder 3 due to motion derived from the cam shaft 1 and translated through the bracket 15 and guide pin 14. By reason of the reverse spiral grooves on the cam shaft 1, as the guide sleeve 10 comes to one end of the cam shaft it is immediately reversed and travels to the other end of the cam shaft. This reversal, however, it will be seen, does not necessitate any reversal of mechanical parts, for the cam shaft 1 is at all times turning in the same direction and the endless spiral grooves 2 automatically change the direction of guide sleeve travel.

I will now endeavor to describe a preferable embodiment of the rotary recording head 5, which may be also determined by the consideration of Figs. 2, 3 and 4 showing both details thereof and conventional embodiments for illustrating the principle of the invention. The rotary recording head 5 preferably consists of two parts generally designated 6 and 7 of which 7 is the portion serv-

ing to guide the recording head 5 in its longitudinal motion with respect to the cylinder 3 and the part 6 is the part for conducting the recording medium (in this case the air) to the recording point proper. The two parts 6 and 7 of the recording head 5 are joined together by means of several tie-rods 78 and are arranged to space the two portions 6 and 7 at any desirable distance apart. In the portion between the two parts of the recording head by arrangements of suitable bracket members to be hereinafter described, I prefer to mount the recording instrument which, in the case illustrated, is that of a plurality of hot and cold air jets for directing a heated air blast against the recording surface and dissipating the heat in accordance with cold air regulated in accordance with various signal intensities.

To now describe the part 6 of the recording head and in this connection to refer to the right hand portion of Fig. 2 in conjunction with the showing in Fig. 1, the recording medium is led from a hose 16 to a tube 17 having a supporting block 98 for rigidly holding the same mounted upon the guide sleeve 10. At the end of the tube 17, and by any suitable arrangement of joints the air coming from the hose 16 is led into a bevelled ring 18 having an opening 19 therein. The opening 19 is formed in Y formation at its inner end. The ring 18 is held securely with respect to rotary motion by means of a bracket 20 carried by the guide sleeve 10 and having a connection from the outer end thereof to the ring 18, so that the ring 18 is fixed and unable to assume any rotary motion with respect to rotation of the rotary recording head 5. Carried on the cylinder 3 is a large ring 21 provided with a recess or groove 22 extending about the circumference thereof and arranged so as to receive air through the Y shaped opening 19, and also leading into this recess or groove 22 are tubular openings 23 formed within the sleeve 21. The ends of the tubular openings 23 are provided with threads so that a connection may be made to one of the recording means and as shown in Fig. 2. The connection is by way of any preferred type of joint 24, through which air coming through the opening 19 and into the recessed or grooved portion 22 is led into the tube 23 and through the joint connection 24 is carried to a conducting tube 25. For the purpose of making the arrangement airtight I have chosen to make the ring 18 of a bevelled construction, as illustrated by Fig. 2, and tightly fix this ring with respect to the sleeve 21 by means of a ring 26 threaded to the sleeve 21 having its bevelled face extending in a direction opposite that of the bevel on the ring 18 and, also, by means of a second ring 27 having a like construction to that of ring 26 and also threaded upon the sleeve portion 21. The small ring 28 is provided for locking the

ring 26 and a ring 29 for locking the ring 27 in its desired position.

Carried by the bracket member 20, as above described, is a locking means for preventing rotational motion of the ring 18 provided for carrying air to the recessed or grooved portion of the sleeve 21 so as to provide an air chamber therein. Also, associated with this locking means is a lubricating system 130 for feeding grease or very heavy oil into the air chamber so that this may be covered with a thin film of grease or oil and provide a means for reducing the friction between the rotating locking rings 26 and 27 and the fixed ring 18 as well as to provide a means for maintaining constant pressure within the recessed or grooved portion 22 of the sleeve 21 by reason of the fact that air confined therein is not permitted to leak out.

To now again refer to Figs. 1 and 3 more specifically the sleeve 21 also has other air connections, as those shown by Fig. 4 and it will be noted that two of the connections are provided with needle valves 30 for regulating the amount of air which passes through the connection 24 and into the tubes 25 for the purpose of regulating the amount of air supplied to the cold air jets.

To now describe the recording mechanism, the same consists of a pair of hot and cold air jets in which each hot air jet is continuously projecting a heated air blast outwardly and in which each cold air jet directs a cold air blast across the path of the hot air jet to dissipate the hot air in accordance with the variations in signal intensity. A conventional showing of a preferred embodiment of my arrangement consisting in a pair of hot air jets and a pair of cold air jets is indicated by Fig. 4 and it will be noted that the hot air jets 31 and 32 are directed in diametrically opposite positions. The air issuing from these jets 31 and 32 is preferably heated by means of heating coils 33 and 34 which may be connected in series and surround the tube carrying air within the heating element 35. The heating element preferably is mounted upon brackets 36 supported from the tie-rods 8 supporting the two portions of the rotary recording head 5, and includes a heat radiating surface 77 surrounding the heating coils. The surface 77 is provided with various openings 79, for the purpose of forming a surface which readily radiates heat. Without the surface 77 readily radiating heat, the heat developed by the heating coils 33 and 34 would be so excessive as to tend to burn out the heating coils as well as the entire machine. It is thus seen that air entering into the heater element 35 from the tubular members 25 is heated and finds a free passage through the heater elements in opposite directions through the hot air jets 31 and 32 to the nozzle portions 36 and 37 where it is projected outwardly with a considerable velocity. The coils for heat-

ing the air passing through the heater element are connected with an energy source through a commutating means associated with the portion 7 of the rotary recording head in a manner to be hereinafter set forth.

5 For the purpose of controlling the amount of heat effective on the recording surface issuing from the nozzle portions 36 and 37 of the jets 31 and 32 I have arranged a plurality 10 of cold air jets 38 and 39 having nozzle portions 40 and 41 directing a cold air blast across the path of the heated air issuing from the nozzles 36 and 37. For the purpose of regulating the amount of air entering the cold air 15 jets 38 and 39 I have provided each cold air system with needle valves 30 which may be of any desired and known form and capable of being regulated with considerable accuracy. The cold air jet is preferably of 20 similar characteristics to those which were disclosed by my copending application, Serial No. 128,720, filed August 12, 1926.

The cold air jets have air carried to them through the connecting tubes 25 to a port 42 25 above the air jets 38 or 39. From this port air is directed into a small iron cylinder 43 having a central opening 44 extending longitudinally therethrough. Directly below the iron cylinder 43 is an electromagnetic valve, 30 generally designated 45, and comprises the cylindrical stem 46 having a flute 47 on diametrically opposite sides thereof through which air may pass. Toward the bottom of this valve there is a necked portion 48 into 35 which incoming air from the supply tube 25 is passed. The air is held within the chamber 49 by the valve proper 50. The valve 50 is provided with a conical seat portion 51 resting upon a valve seat 52 of the valve sup- 40 porting structure. Directly below the valve seat is a second air chamber 53 from which leads the connecting passage 54 to the air di- 45 recting the nozzles 40 or 41. The upper part of the valve and its supporting structure to- 50 gether with the iron cylinder is enclosed by a cylindrical casing 38 or 39 carried by the sup- 55 ports 36 which is also used for supporting the hot air jets. Carried also by the enclosing structure or casings 38 or 39 is an electro- 60 magnet 55 to which current is supplied through the leads 56, 57. When the current is supplied to the magnet 55 the valve 45 will be drawn upward so as to bring the valve seat 51 into a closed position whereby air is 65 unable to flow. However, upon a decrease of current strength in the magnet the valve 45 will be released and dropped so that air may pass from the supply tube 25, through the chamber 42, through the opening 44, into the cylinder 43, through the fluted portion 47 of the valve 45 and into the chamber 53 from 70 which it is passed outwardly through the nozzle 40 or 41. The supply of cold air in the case is extremely even due to the air cushioning effect in the chamber 53 which is caused

by making the opening into the nozzle 40 or 41 relatively small supplying air at a rapid rate, and in fact the air is entering the air chamber faster than it is leaving. The connections for controlling the magnet will be 75 hereinafter described in conjunction with the connections for the heating element for the hot air jet but it will be now stated that the cold air is controlled by variations in the various signal intensities influencing a receiver of any suitable character.

It is thus seen that the hot air is continuously being projected through the nozzles 36 or 37 and that at interrupted periods cold air issues from the cold air jets 40 and 41 in such a manner such as to project cold air across the path of the hot air. Each of the hot air jets have their nozzle portion arranged so that it will point directly into one of the slotted portions 8. When the rotary 85 recording head 5 is moved longitudinally of the cylinder 3 by means of the rotary cam shaft 1 and associated guide sleeve 10 and the pin 14 resting in the slot 13, the recording jets will traverse a path corresponding to 90 either slot 8 or 9 in the semicircular shaped plate member 7. It will thus be seen that if a recording surface of the character above set forth is carried on the back side of the semicircular shaped plate member 7 and ad- 95

vanced with respect thereto at a predetermined rate of speed that it will be subject to the action of heated air from the jet 37 as shown in Fig. 1. Now if we assume that the rotary recording head is turning in a clockwise direction as indicated by the arrow on Fig. 1, and that the recording head at the left end of its longitudinal travel on cylinder 3, the nozzles 37 and 41 will trace a path along the slot 8 from point "A" downwardly in the direction of the arrow until the nozzle reaches a point corresponding to "A" at the other end of the slot 8, in which case the second nozzle system 36 and 40 (not shown by Fig. 1) will have moved in a rotary direction as well as longitudinal due to the rotary and longitudinal motion of the recording head 5 with respect to the cylinder 3 until these nozzles have reached a point corresponding to "B" on Fig. 1. From this position the nozzle system 36 and 40 will trace a path for recording along the slot 9 from right to left (looking at Fig. 1) starting at point "B" in the direction of the arrow until the nozzle system reaches the end point of slot 9 which corresponds to point "B", but which is at the other end of the semicircular shaped plate member 7. Under these conditions the nozzles 37 and 31 have been so moved as to be in a position to trace a recording path along the slot 8 from "A" in the direction of the arrow first mentioned. It is thus seen that when the recording head is rotated and moved longitudinally back and forth on the cylinder 3 that the recording mediums or air jets will 130

continuously trace a jet path for recording impulses which extends first from left to right and then from right to left and at an angle to each other and that if a recording surface is carried by the plate member 7 and continuously advanced at a predetermined rate of speed that it will carry marks in which each consecutive direction of marking is at an angle to the previous direction of marking and in which each successive marking in the same direction is in a line parallel to that of the previous direction of marking. In connection with this type of arrangement, I, of course, intend to use a recording surface or paper which is sensitive to the action of heat and one which will produce clean cut marking impulses when subjected to various intensities of heat such as are occasioned by the variations in the amount of heat directed which is in turn controlled by the amount of cold air dissipating the heat issuing from either the jets 36 or 37.

Fig. 5 of the drawing illustrates in a conventional manner the various paths of recording action upon the continuously advancing recording surface. The arrow on Fig. 5 indicates the direction of the continuous advance of the recording surface and the odd numerals 101, 103, etc., indicate the direction of recording of the recording means in a direction from left to right diagonally across the recording surface and the even numerals 102, 104, etc., indicate the diagonal motion of the recording means across the recording surface in a direction from right to left. It will be noted, upon an examination of Fig. 5, that each recording action takes place as two groups of intersecting parallel lines. To trace the recording action in the manner in which the sensitive recording surface is subjected to the recording, the paths of recording are in numerical order, for example, recording takes place upon the line 101, then upon the line 102, then upon the line 103, etc., until the entire picture received has been recorded and produced in the form of an interwoven mesh which will produce in its finished form the appearance of the desired half-tone picture.

To now describe the system for controlling the heat projecting jets and the signal actuated cold air jet I preferably provide an arrangement which I have termed a "commutator" and which consists, as shown, of four conducting ring members 58, 59, 60 and 61 separated by insulating rings 62 of any desired characteristics although by suitable arrangements a lesser number of rings might be used. These commutator rings are carried by the portion 7 of the rotary recording head 5 and are mounted or fastened to the slotted portion 13. As shown by the drawing, a brush member 63 is carried by the bracket frame 15 which is used for guiding the recording head in its longitudinal motion with

respect to the cylinder 3. The brush portion consists, in the arrangement shown, of four contact members for making contact with the various portions of the commutator, and each contact segment of the brush 63 is separated in a manner similar to that shown in the commutator by a layer of insulating material. The bracket 64 on the guide sleeve 10 serves for fastening the electrical connections to the brush members and these connections preferably consist of four lead wires 65, 66, 67 and 68 intertwined to form a single cable 69 and having connections to the brush member.

As shown, the cables 65 and 66 are associated with the commutator rings 58 and 59 to form a signal circuit, and the cables 67 and 68 associated with the rings 60 and 61 to form the heating circuit. To the inner portion to each of the ring numbers 58, 59, 60 and 61 a connection of any desired type is made, as, for example, from the ring 60 one connection is made to the heating element 35 and from the ring 61 a second connection to complete the circuit. Similarly, connected to the inner portion of each of the rings 58 and 59 connections are made to the electromagnetics controlling the cold air jets 38 and 39 in accordance with signals received through leads or conductors 65 and 66 and it is through these connections that the cold air jet is affected by incoming signals varied in accordance with the intensity of light and shade in a transmitted picture affecting a receiving apparatus circuit (not shown).

I have now described the method of operation of my arrangement in its entirety but it may herein be set forth that a preferable arrangement consists in arranging the hot air jets and associated heater elements 35, 37 in the slotted portion 4 of the cylinder 3, since these elements are at all times rotating at a speed corresponding to that of the cylinder. The signal actuated cold air jets are preferably placed outside the cylinder and rotated in accordance with the rotary sleeve 21, which is at the same speed as the rotation of the hot air jets.

For the purpose of enabling the rotary recording head to travel in its reciprocating and longitudinal motion with respect to cylinder 3 with the minimum friction I have provided a series of brackets 70 on each end of the rotary recording head and in these brackets are mounted a series of rollers 71, which rest upon and are guided in their motion upon the cylinder 3 so as to form a roller bearing surface for the recorder. Thus, a roller bearing surface for the longitudinal motion of the recording head 5 in cylinder 3 is provided.

A method and an arrangement for mounting the ends of the cylinder 3, the cam shaft 1, as well as the guide spindle 12 and the semicircular shaped slotted plate member 7

has not been shown since it is believed that it is unnecessary to complete understanding of the invention and would do nothing more to complicate the case but may consist in 5 end supporting plates and associated drive for the rotary elements connected thereto. For reference to a showing of the above described supporting means which is of a similar nature, but relating to a transmitting 10 apparatus arrangement, I will herein again make reference to the showing in my copending application, Serial No. 235,431, filed November 25, 1927.

It will be noted from the description that 15 in the recording action each point in the picture is recorded at two separate intervals of time and that the various intensities of light and shade in the transmitter picture are twice reproduced, each reproduction 20 being in a direction bearing an angular relationship with respect to the other direction. This provides an effective method for avoiding the detrimental effects of static and fading due to conditions of the atmosphere 25 since fading and static are shown by many experiments to be different at different periods of time and if the marking impulse at one point of recording is bad due to these conditions the probability is that these conditions 30 will be better or at least as good at the next period of recording. Therefore, an arrangement has been produced in which the accuracy and efficiency of reproduction is considerably increased, and the difficulties of 35 sending a picture two or three times due to poor reception are avoided.

For the purpose of synchronization, the 40 system may employ any desired type of synchronizer of which tuning forks or air driven synchronizers of the character disclosed in the copending application, Serial No. 169,620, filed February 19, 1927, or appropriate types of visible indicators are suitable. The specification does not specifically 45 disclose any type but it is to be understood that for the purpose of disclosing my invention I may broadly refer to a synchronizer as embodying any of the known types of arrangements for coordinating the speeds of 50 rotation of similar moving elements at the transmitter and receiver, so that while one part of a picture is being explored at the transmitter an identical or appropriately coordinated part is being reproduced at the 55 receiver.

Having thus described my invention I am 60 entitled to all modifications such as fall fairly within its spirit and scope as defined by the following claims wherein—

60. I claim:

1. The method of recording pictures, which includes, controlling a plurality of recording 65 mediums in accordance with received signal pulses, and directing the recording mediums to alternately trace marks on a re-

cording surface in two directions bearing an angular relationship with respect to each other.

2. The method of recording pictures, which includes, receiving signals of varying intensities in accordance with the intensities of light and shade in a picture being transmitted, alternately and independently tracing marks varied in intensity in accordance with the intensities of said received signals in two directions bearing an angular relationship one with the other and crossing each other on a recording surface and continuously advancing the recording surface with respect to the marking, whereby the recording is produced as two groups of parallel lines in which the lines of one group intersect the lines of the other group. 70

3. The method of reproducing pictures in accordance with received signal impulses, which includes, reproducing marks varied in intensity in accordance with light and shade of an original picture as affecting received signal pulses, directing said marks in a line bearing one direction with respect to a recording surface, and at a later period of time independently directing marking pulses in a line bearing an angular direction with respect to the first line of marking pulses and intersecting said first line of recording. 75

4. The steps in the method of receiving transmitted pictures, which includes, alternately and independently recording the received picture along two intersecting paths each of which bear an angular relationship 80 with respect to each other. 100

5. The steps in the method of recording transmitted pictures, which includes, twice recording by independent recording actions the received picture point for point along a pair of sets of parallel lines each intersecting the other in predetermined points. 105

6. The steps in the method of receiving transmitted pictures, which includes, influencing independent signal recorders at different periods of time in accordance with various point for point light intensities in an original picture, and independently recording each variation of the independent recorders in a point for point relationship to portray the varying light intensities in the original picture transmitted as a pair of groups of intersecting parallel lines. 110

7. The steps in the method of receiving transmitted pictures, which includes, influencing independent signal recorders at different time periods in accordance with various point for point light intensities in the picture being transmitted, recording from one recorder the point for point light intensities in one direction, independently recording from the other recorder at a later period of time the intensities in another direction, and superimposing the two said recordings one 120 125 130

upon the other as an interwoven set of groups of parallel intersecting lines.

8. The steps in the method of receiving transmitted pictures, which includes, recording a picture point for point alternately and independently along lines in two directions intersecting each other at predetermined positions continuously advancing a recording surface with respect to and during the recording 5 action for producing a finished picture recorded in a series of parallel lines each intersecting each other and producing a recorded picture having the appearance of half-tone.

9. An apparatus for the reception of transmitted pictures, including, means for recording the transmitted picture point for point along a line in one direction, and means independent of said first named means for recording said picture at a later period of time 10 point for point along a line in a second direction bearing an angular relationship to the line of said first direction and intersecting said first line.

10. An apparatus for the reception of transmitted pictures, including, means for recording a picture first in one direction and at a later period of time recording the picture in a direction bearing an angular relationship to said first named direction of recording, said recording means including an air operated recorder arranged to move with respect to a recording surface first in one direction and at a later period of time in another direction, a recording surface, and 25 means for continually advancing said recording surface for said picture with respect to said recording means.

11. In an apparatus for recording transmitted pictures, means for recording a picture diagonally in one direction, a second 40 means for again recording the picture diagonally in an opposite direction, a recording surface, and means for advancing the recording surface continually with respect to the recording means.

12. In an apparatus for recording transmitted pictures, a recording surface, means for recording a picture in one direction on said surface, a second means for recording a picture 50 on said surface in a direction bearing an angular relationship to said first named direction, means for varying the operation of said recording means in accordance with received signal impulses corresponding to picture tones, and means for continually advancing the recording surface with respect to the recording means.

13. An apparatus for the reception of transmitted pictures, which includes, a supporting 60 member provided with a plurality of intersecting slots, a recording surface carried by said supporting surface and advanced continually with respect thereto, a recording means supported beneath said support, means 65 for advancing said recording means to trace

a path on said recording surface corresponding to the slots in said support, and means associated with said recording means for varying the recording action of said recording means on said recording surface in accordance with received signals, whereby a received picture is built up in accordance with the variations in light and shade in a transmitted picture.

14. An apparatus for the reception of transmitted pictures, including, a semicircular elongated supporting surface, said surface being provided with a plurality of slots arranged at an angle with respect to each other, a recording surface carried by said support and advancing continually with respect thereto, a rotary cylinder carried beneath said supporting surface, a rotary recording head mounted upon said cylinder and deriving rotary motion therefrom, means for advancing said rotary recording head longitudinally of said cylinder in conjunction with said rotary movement, a recording instrumentality carried by said rotary recording head and arranged to trace a path on said recording surface corresponding to the slots in said support surface and thereby influencing said recording surface, and a commutating means associated with said rotary recording head for controlling the action of said recording means on said recording surface in accordance with variations in received signal pulses.

15. In an apparatus for recording transmitted pictures, a semicircular shaped elongated supporting plate, a plurality of slots arranged in said plate and extending across the surface of said plate so as to cross each other at approximately their mid-point, a recording surface carried by said supporting plate and advanced continuously with respect thereto, a recording head beneath said supporting plate, means for moving said recording head to trace a path on said recording surface corresponding to the slots in said supporting surface; a plurality of air-controlled recording elements carried by said recording head, and means for controlling the action of said air recorders on said recording surface in accordance with received signal pulses.

16. In an apparatus for receiving transmitted pictures, a recording surface, a support for said recording surface, said support being provided with a plurality of slots arranged at an angle with respect to each other and crossing each other at approximately their mid-point, a recording head carried beneath said support plate, said recording head being provided with a plurality of hot air jets arranged at diametrically opposite points on said recording head and a plurality of cold air jets arranged to each project a cold air blast across one of said hot air jets, means for moving said recording head and associated air jets for causing said jets to trace a path with respect to said support plate

corresponding to the slots in said support plate, and means for controlling the action of said cold air jets in accordance with received signal pulses, whereby the said hot air issuing from said hot air jet is dissipated in accordance with received signals and the action of said jet through said slot on said recording surface is varied.

17. An apparatus for recording pictures, a 10 semicircular shaped elongated supporting plate, a plurality of slots arranged diagonally with respect to said plate and extending in opposite directions with respect thereto, a recording surface carried by said plate and 15 continuously advanced with respect thereto, a recording head carried beneath said plate and having one point on said head arranged to trace a path on said recording surface corresponding to the slots in said supporting 20 plate, said recording head including an air chamber, a plurality of connections to said air chamber, a plurality of pairs of air jets for directing air carried by said recording head, said jets being arranged so that each 25 pair direct the air at diametrically opposite points on said recording head, means for heating the air in one jet of each of said pairs of jets, and means controlled by the other said jet in each of said pairs for dissipating 30 the heat issuing from said first named jet in accordance with variations in received signals.

18. In an apparatus for recording transmitted pictures, a recording surface, means 35 for recording pictures on said surface first in one direction and at a later period of time in a direction bearing an angular relationship to said first named direction, said recording means including a plurality of hot and cold 40 air jets arranged to pass directly beneath said recording surface and mark said recording surface in accordance with the variations in light and shade in a picture, and means for controlling the action of said cold air jets in 45 accordance with received signals.

19. The steps in the method of receiving transmitted pictures, which include, recording a picture point for point alternately and independently along lines in two directions 50 each intersecting the other at predetermined positions, continuously advancing the recording surface with respect to the recording action and during the recording action for producing a picture recorded as a series 55 of lines extending in two directions and forming two groups of intersecting parallel lines.

20. A picture recording apparatus, including, a support surface for a picture recording medium, means for continually advancing 60 the recording medium with respect to said support surface, means for tracing on the supported recording medium a record extending diagonally across the record surface in one direction, means for tracing a record 65 diagonally across the recording medium in

a direction intersecting said first named direction, and means provided by said continual advance of said recording surface for alternately tracing records on said recording surface corresponding to said above named records and producing a recorded picture formed from a pair of groups of interwoven and intersecting parallel lines.
